NONSANDING PUMP

Anthony E. Carlson, Los Angeles, Calif.

Application October 18, 1932, Serial No. 638,297

1 Claim. (Cl. 103—225)

My invention relates to deep well pumps of reciprocating type such as extensively employed in oil and water wells. The invention has its principal utility in pumps employed to pump oil 5 from deep wells.

Pumps of the character to which the invention relates employ a cylindrical barrel and a reciprocating plunger or piston. The piston is also of cylindrical construction and has sealing 10 means on the exterior thereof for sliding engagement with the inner face of the pump barrel. In some pumps the external sealing means of the pump piston consists merely of a metal wall of a size to closely fit the barrel; whereas, 15 in other pumps the external sealing means of the piston is formed by use of annular bodies of flexible or adjustable material, such as represented by cup washers. Although my invention applies to both of the above set forth general 20 types of pumps, it is of especial utility in pumps employing cup washers as the external sliding sealing means of the piston or plunger. Owing to the expansibility of the cup washers, pumps of this type are very satisfactory where 25 the fluid pumped is relatively free from sand or other abrasive or solid materials; but where the fluid pumped, such as oil, contains sand or other solids, such solids will accumulate behind and above the cup washers so as to force the cup washers outwardly against the pump barrel with 30 such pressure that either the cup leathers are rapidly worn away or the pump plunger becomes frozen in the barrel, with the result of breakage of the string of sucker rods and the 35 necessity of removal of the pump from the well. In sleeve-type pumps employing solid pistons the accumulation of sand between the walls of the piston and of the barrel produces rapid wear and sometimes results in sticking of the pump 40 barrel. This wear of the barrel and the piston rapidly reduces the pumping efficiency due to leakage of oil around the piston.

My invention comprehends a pump piston of cylindrical or tubular form having sealing means 45 on the exterior thereof adapted for sliding engagement with the pump barrel, in conjunction with check valves, preferably of the ball type, disposed at or near the upper and lower ends of the piston to prevent a reverse flow of fluid 50 through the axial passage formed through the piston, and openings through the tubular wall of the piston providing communication between the interior and the exterior of the piston for lubricating the intermediate portions of the external face of the piston and for removing the

sand which tends to accumulate on the exterior of the piston.

Since I believe my invention to have its greatest utility with a pump structure employing cup leathers as the external piston sealing means, 5 I shall hereinafter disclose and describe a simple form of the invention in which the tubular piston has a plurality of cup leathers mounted thereon to serve as sealing means in sliding engagement with the pump barrel, and openings 10 through the tubular wall of the pump piston adjacent the inner faces of the cup washers so that sand which tends to accumulate in the annular spaces formed within the cup washers may be washed into the interior of the pump piston 15 during the return or down stroke thereof.

Further objects and advantages of the invention will be made evident throughout the following part of the specification.

Referring to the drawing, which is for illustrative purposes only,

Fig. 1 is a sectional view showing an embodiment of my invention in use in a deep well pump having a removable barrel.

Fig. 2 is an enlarged fragmentary cross section of the upper end of the piston disclosed in Fig. 1.

Fig. 3 is a cross section on a plane represented by the line 3—3 of Fig. 2.

Fig. 4 is a cross sectional view similar to Fig. 30 2, showing an alternative means for securing the parts of the pump piston together in operative relation.

Fig. 5 is a fragmentary cross sectional view 35 showing the manner in which the external sealing means may consist of a number of cup leathers in superimposed relation.

In Fig. 1 of the drawing I show the lower end 40 of a vertical tubing or pipe 11 extending down into a well, such as an oil tubing commonly used to support a pump in operating position. By means of a fitting 12, a pump receiver 13 is secured to the lower end of the tubing 11, this pump receiver 13 consisting of a pipe 14 having a seat 15 at its lower end. In the pump receiver 13 45 is a pump barrel 16 having a valve fitting 17 at its lower end engaging the seat 15 and being provided with a ball 18 to form a foot valve for the pump. The upper end of the barrel 16 is provided with a fitting 20 which carries a conical packing member 21 adapted to engage a conical face 22 of the fitting 12 so as to seal between the upper end of the pump barrel 16 and the upper 50 end of the pump receiver 13. The fitting 20 at 55

the upper end of the barrel 16 provides an inwardly extending shoulder 23.

Within the barrel 16, the lower end of a sucker rod string 25 extends and is secured to the upper 5 end of my new pump piston or plunger 26 which has external sealing means 27 thereon for sliding engagement with the inner face of the barrel 16. The sealing means 27 are preferably in the form of cup washers or cup leathers each, as shown in 10 Fig. 2, having a cylindrical wall 28 for engaging the barrel 16 and an inwardly turned radial flange 30 by which the cup washers are secured to the pump piston 26 between shoulders of cooperating parts of the piston which are adapted to 15 be secured together in consecutive order. As best shown in Fig. 2, the upper end of the piston 26 consists of an annular wall 31 adapted to be secured to the lower end of a tube 32 which forms the upper portion of the plunger and extends 20 from the upper end of the barrel. On the upper end of the tube 32 is a yoke member 33 through which the oil may pass into the oil tube 11, having a threaded box 33a by which it is connected to the lower end of the string of sucker rods 25. The lower end of the member 31 is turned down so as to provide a tubular extension 34 projecting downwardly from a radial shoulder 35 and being externally threaded for connection 25 to a sleeve section 36 which is provided with 30 internal threads 37 at its upper end to fit the threads of the extension 34 of the member 31. When the members 31 and 36 are screwed together, the flange 30 of the cup washer 27 is gripped between the shoulder 35 and a shoulder 38 at the upper end of the member 36. Adjacent the inner face of the cup washer 27 a shallow annular channel 40 is formed in the external face of the member 31, and openings 41 connect this annular channel 40 with the interior passage 40 or channel 42 of the member 31. A valve seat 43 is held against a shoulder 44 disposed within the sleeve member 36 near the lower end thereof by means of an annular member 31a having a threaded extension 45 which screws into the 45 lower end of the sleeve member 36. The annular member 31a is the same as the annular member 31 with the exception that the yoke member 33 is replaced by the threaded extension 45. Against the radial shoulder 35 of the member 31a a second cup washer 27 is held by means of a succeeding sleeve member 36. Each of the sleeve members 36 has a valve seat 43 therein and contains a valve ball 46. To limit the upward movement of each valve ball 46, the lower end of each fitting 31 or 31a may be provided with a diametrically extending bar 47 which may readily consist of a pin extending through openings 48 in the extension 34.

60 In the manner above described the piston 26 consists of consecutive sections joined together to form a continuous tubular structure. Each of the sections has the sealing means 27 at the lower end thereof, and below the planes of the radial openings 41 adjacent the inner faces of the sealing means or cup washers 27 valve means 50 represented by the seats 43 and balls 46 are disposed to control the flow of fluid through the axial passage of the piston 26. During the upward stroke 65 of the piston each of the valve means 50 is closed so that each of the cup washers in consecutive order may support a body of oil against the under face of the preceding cup washer, thereby dividing the pumping load between the series of cup washers with which the piston 26 is provided.

For example, should the piston have five cup washers thereon and be operating against a head of one thousand pounds per square inch, the pressure in the spaces 85, 86, 87, etc., between the consecutive cup washers may be nine hundred, 5 eight hundred, seven hundred, etc., pounds per square inch, the pressure in each space being applied to the under face of the cup washer at the upper end thereof so that the differential of pressure between any two spaces is maintained 10 at a small amount, such as one hundred pounds per square inch. It will be recognized that the length of the piston may be varied to suit operating conditions and that the number of cup washers employed in the assembly may be readily varied. As shown in Fig. 1, the lowermost sleeve 36 has its valve seat 51 held therein by a simple bushing 52.

The operation of the piston may be determined from the following. It is a well known fact that sand in oil being pumped accumulates in the annular spaces formed adjacent the inner faces of the cup washers 27 and packs tightly therein, with the result that the cup washers are forced outwardly with great pressure against the pump barrel. In my pump the annular channel formed adjacent the inner face of each cup washer 27 is in direct communication with the interior or axial passage of the piston so that sand which accumulates in the space provided by the annular channel 40 may pass into the interior of the piston 16 during the downward or return stroke thereof. During this downward stroke of the piston, oil passes upwardly through the piston as indicated by the arrow 53, thereby producing a suction adjacent the inner ends of the radial openings 41, with the result that oil is drawn from the annular channel 40 through the passages 41 into the upward flow of oil through the interior of the piston, carrying therewith such sand as may 35 accumulate in the annular channel 40.

In Fig. 5 I show the manner in which each pumping cup washer 27 may be preceded by a surface cleaning cup washer 27a. This is accomplished by placing between the upper end of a sleeve 36 and a fitting 31a a fitting 54 which is similar to the fitting 31a with the exception that it is provided with a threaded counterbore 55 to receive the threaded extension 34 of the fitting 31a. The cleaning cup washer 27a is gripped 50 between the shoulder 56 at the upper end of the member 54 and the radial shoulder 35 of the fitting 31a. The washer 27a has no pumping effect but merely removes sand from the face of the barrel 16 ahead of the washer 27, thereby minimizing the wear on the cup washer 27. It will be readily seen that the pump piston 26 has means for preventing the accumulation of sand adjacent the external sealing faces of the piston which operate in sliding engagement with the inner face 60 of the pump barrel and therefore will operate with a minimum of wear since the pressure of the cup washers 27 against the inner face of the barrel 16 is determined only by oil pressure and not by pressure of accumulated sand or other foreign materials, and that the piston cannot become frozen or sanded up under ordinary operating conditions.

Accumulation of sand between and adjacent the frictional engaging faces of the piston and 70 barrel of a pump of the general character now in use produces a friction load in addition to the pumping load of the head of oil being moved upwardly through the pump tubing by the piston. For example, this friction may produce a resist- 75

ance against upward movement of the piston equal to the pressure of the oil so that the sucker rods and pumping mechanism are forced to carry twice the load which would be carried were the 5 piston operating freely. As the sand accumulates, the friction load becomes greater and greater until finally the piston is relatively immovable; and as the friction load increases, the elongation of the string of sucker rods at each pumping stroke 10 increases so that the sucker rods become fatigued in a much shorter length of time than where they are operating under conditions of free movement of the piston within the pump barrel. My new pump, by preventing accumulation of sand on the 15 exterior of a pump piston, keeps the friction load at a minimum, thereby maintaining the power required for pumping at a minimum, minimizing the elongation of the string of sucker rods, and accordingly increasing the production of oil. It 20 will be recognized that where the friction load is great and the sucker rods are correspondingly stretched, the movement of the piston within the barrel is reduced so that its pumping effect is correspondingly reduced. By keeping the friction 25 of the piston at a minimum point, a maximum movement of the piston is maintained, with the result of a maximum production of oil from the well.

In Fig. 4 I show an alternative construction 30 whereby the results specified relative to the form of the invention shown in Fig. 1 may be obtained. The piston 60 has at its upper end an annular member 61 adapted to be secured to the lower end of the tubular member 32 which extends upwardly within the pump barrel 16 and further serves as a guide means for the piston or plunger. The annular member 61 has an inner cylindrical surface 63 leading upwardly from its lower end to internal threads 64 which are spaced from its 40 lower end as shown. Secured to the lower part of the annular member 61 is a sleeve or section member 65 having a tubular extension 66 of reduced diameter having a threaded upper end 67 so that the extension 66 will project within the 45 cylindrical face 63 and engage the threads 64 of the member 61. Between shoulders 68 and 70 provided respectively by the members 61 and 65 cup washers 71 are gripped so as to be held in operating position. Adjacent the inner face of 50 each cup washer 71 radial openings 72 are provided through which oil may circulate so as to remove sand which tends to accumulate within the cylindrical portion of the cup washer. The section member 65, like the member 61, has a cylindrical face 63 within the lower end thereof 55 followed by threads 64 so that the tubular extension 66 of a following section 65 may be secured thereto in the same manner as the first of the sections 65 is secured to the member 61. Within each of the sections 65 valve means 74 60 are disposed, the seat member 75 of each valve means being held in place against a shoulder 76 by the upper end of the tubular extension 66 of the succeeding section member 65. To limit the upward movement of the valve means 74, pins 78 65 may be placed diametrically across the section members 65. For any given size of pump a valve

ball of relatively large size may be employed, since such valve balls are disposed within the sleeve or section members 36 or 65.

As will be noted in Figs. 2 and 4, the upper end of each annular member 31 and 61 provides a 5 shoulder 62 which projects beyond the surface of the tubular member 32 so that when the piston 26 is lifted above its ordinary working position within the barrel 16, the shoulder 62 will engage the shoulder 23 of the fitting 20 and lift the barrel 10 15 from the barrel receiver 13. The yoke member 33 has a shoulder 90 adapted to engage the upper end of the fitting 20 before the lower end of the piston can engage the valve mechanism at the lower end of the cylinder 16, so that the force required to seat the barrel 16 in the barrel receiver 20 may be transmitted from the sucker rods to the barrel 16 without possibility of injuring any part of the piston 26 and so that dropping of the piston through any cause cannot result in the lower end 20 of the piston striking the valve means at the lower end of the barrel 16.

Although I have herein shown and described my invention in simple and practical form, it is recognized that certain parts or elements thereof 25 are representative of other parts, elements, or mechanisms which may be used in substantially the same manner to accomplish substantially the same results; therefore, it should be understood that the invention is not to be limited to the 30 details disclosed herein but is to be accorded the full scope of the following claim.

I claim as my invention:

A pump piston of the character described, 35 adapted to be operated in a pump barrel in a well, including: a plurality of cup washers of a size to fit said barrel, each cup washer having a cylindrical portion and a radial flange portion; a plurality of tubular members having an external diameter nearly as large as the internal diameter 40 of said barrel; cooperating threaded means at the ends of said tubular members for connecting them together to form a piston having a passage for pumped liquid extending from end to end thereof, there being valve seat receiving shoulders 45 associated with said threaded means for positioning and sealing valve seats within said tubular members, there being cooperating external shoulders formed in conjunction with said threaded means for engaging said radial flange portions 50 of said cup washers when said threaded means are screwed together to connect said tubular members in end-to-end relationship, and there being a group of small openings disposed in the wall of said piston behind each of said cup washers connecting the inner wall of each cup washer 55 with the passage through said piston; a plurality of annular valve seats, the number of said valve seats corresponding to the number of said cup washers, and one each of said valve seats being 60 held in place in said passage of said piston by said valve receiving shoulders below the plane of the cup washer to which it corresponds; and a valve closure member disposed above each of said valve seats for closing engagement therewith. 65

ANTHONY E. CARLSON.
